(57) **CLAIM**

The ornamental design for a transition adapter for electrical conduit, as shown and described.

DESCRIPTION

FIG. 1 is a top perspective view of a transition adapter for electrical conduit, showing our new design;

FIG. 2 is a bottom perspective view thereof;

FIG. 3 is another top perspective thereof;

FIG. 4 is a top plan view thereof;

FIG. 5 is a bottom plan view thereof;

FIG. 6 is a side elevation view thereof, the opposite side being a mirror image thereto; and,

FIG. 7 is a side elevation view thereof, taken 90 degree from the view of FIG. 6, the opposite side being a mirror image thereto.
